Primary Examiner — Karen E Kearney*Assistant Examiner* — John Reickel(74) *Attorney, Agent, or Firm* — Nwamu, P.C.(57) **CLAIM**

The ornamental design for a computer display with graphical user interface, as shown and described.

DESCRIPTION

FIG. 1 is a front view of our new design for a computer display with graphical user interface; and, FIG. 2 is a front view of our new design for a computer display with graphical user interface according to a second embodiment of the present invention.

The dashed broken lines are for the purpose of illustrating portions of a computer display and window for displaying the graphical user interface and form no part of the claimed design.
